HEATED FORM FOR PROGRESSIVELY
CASTING CLAY WALLS IN PLACE

Delmer Whittenberg, Muskogee, Okla.

Application September 12, 1945, Serial No. 615,762

3 Claims. (Cl. 25—131)

1

This invention relates to heated forms for progressively casting tile walls in place, and a method of placing reinforced clay and curing it in place.

The usual method of construction of tile structures is by use of pre-cast blocks laid in the same manner and secured the same as brick in mortar.

An object of this invention is to eliminate this old method and shape the wall with wire mesh reinforcing and then cure the wall in its permanent position.

This method, therefore, will construct homes that are inexpensive, durable, termite-proof and fire proof. Homes can be built with greater speed and less cost with this method than with the methods previously used.

With these and other objects and advantages in view the invention consists of the novel details of construction, arrangement, and combination of parts more fully hereinafter described, claimed and illustrated in the accompanying drawings in which:

Figure 1 is a side elevation of the form and guide embodying the invention.

Figure 2 is a top plan view thereof.

Figure 3 is an end elevation thereof.

Figure 4 is a sectional view on the line 4—4 of Figure 1.

Figure 5 is a sectional view on the line 5—5 of Figure 4.

Figure 6 is a sectional view on the line 6—6 of Figure 5.

Figure 7 is a sectional view on the line 7—7 of Figure 1.

Figure 8 is an elevational view of the pump or mud jack partly broken away.

Figure 9 is a fragmentary view showing a pre-cast tile in the wall to shape the openings therein.

Figure 10 is a perspective view of the pre-cast tile.

Figure 11 is a top plan view of a form for shaping a corner segment of wall.

Figure 12 is a side and end view of the form and guide for shaping a corner segment of wall, and

Figure 13 is a sectional view on the line 13—13 of Figure 12.

Referring more in detail to the drawings, the reference numeral 20 designates a wall form which is slidably mounted for vertical movement within the frame 22.

The form 20 comprises outer side walls 24, removable end walls 26 and closed top 28. Secured to the top 28 by welding or other means are the inner walls 30 which are parallel to the

outer walls 24, and spaced therefrom transversely the desired thickness of the wall A, which is constructed of clay or similar materials. The walls 26 are made removable so that the clay can be placed against the formed wall section or clay can be placed against clay during the forming of subsequent walls sections.

The inner walls 30 extend longitudinally of the form 20 and are joined at their ends by inner 10 end walls 32 to form vertical tubes or compartments 34.

The outer side walls 24 and the interior of the tubes 34 are covered with asbestos or similar material 36 that have the heating elements 38 embedded therein and current is supplied thereto by the power line 40.

The heating elements 38 on the side walls 24 are positioned intermediate L-beams 42 which are placed at the upper and lower edges of the form 20 and extend longitudinally thereof to function as guides for the form within the frame 22 and the ends thereof are joined by means of L-beams 43.

Extending longitudinally of the top 28 and secured thereto by welding at the medial line thereof is the channel iron beam 44. This beam 44 with the beams 42 serve to strengthen and reinforce the form 20.

A pipe 46 secured to the form at the medial 30 point thereof serves to feed the clay into the form as it is pumped thereto by means of the pump jack 48.

The frame 22 comprises vertical L-beams 50 which receive the beams 42 and function as guides for the form 20 as it uses vertically. The beams 50 are disposed on opposite sides of the forms at the outer ends thereof and are formed at their upper edges by horizontal longitudinally extending L-beams 52 and transverse extending L-beams 54 making a compact unit which is further strengthened by means of the crossed steel strap braces 56.

The ends of the form are provided with half tubes 58 which will coat with other half tubes 45 when the next section of wall is joined to cast the vertical air spaces in the walls caused by the tubes 34 and half tube 58.

The inner sides of the end walls 26 are provided with vertical relatively spaced steel rods 50 60 welded thereto which form vertical grooves in the walls as they are constructed. These grooves are adapted to receive ties to secure alignment of the segments formed by this method in constructing the walls.

Secured to the lower L-beams 42 at an in-

clined relation thereto so that the upper end thereof extends beyond the beams 50 are the roll supporting rods 62, which are adapted to support the rolls of wire mesh 64. The rolls 62 are placed on opposite sides of the form 20 and the wire mesh 64 is fed therefrom to the walls through the longitudinally extending slots 66 formed in the top 28 of the form.

Hooks 68 secure the ends of the wire mesh in position with relation to the form 20 and I-beams 50. At the time the wire mesh 64 is rolled the tin liner 70 is rolled with it so that as the wire mesh 64 is embedded in the wall the liner 70 passes between the inner surface of the outer walls 24 and the wall under construction as shown in Figure 7.

When the wall segment is being formed, the precast tiles 72 are laid at the bottom thereof to form openings to permit blowers for controlling the heat applied to the segment to be inserted therein as shown in Figure 9.

In Figure 1, a block and tackle 74 is shown connected to the frame to lift the form manually when it is desired to move it from location to location.

In Figure 2, the L-beams 52 are notched at 76, where the I-beams are connected thereto to prevent end play and retain the beams in true alignment with each other.

In Figure 7 the connections to the pipe 46 are shown and a flexible pipe 78 is connected to the series of elbows 80 on the pump jack 48 which comprises the housing 82 and screw 84 to which power is supplied through the shaft 86 for forcing the clay into the form 20.

In Figures 11, 12 and 13 the form 90 is L-shaped to construct the corner segment otherwise, the construction remains as previously described, except that the corner tube 92 is formed at the corner of the segment as shown in Figure 13.

The channel iron beam 94 is now L-shaped in form and the pipe 96 is connected thereto as was the pipe 46 to the channel iron 44.

The I-beams 98 lie at right angles to each other and the longitudinally extending L-beams 100 connect their upper ends and their ends are connected by the transverse beams 102.

This invention consists of a heated form 20 for shaping soft clay and partially curing it sufficiently to hold its shape and place until the wall is completed and this is accomplished by the following method of operation:

The clay which has been previously mixed is pumped to the form 20 by means of the jack pump 48 and as the form fills it will rise slowly by the power of the incoming clay forced therein by the pump 48. After the walls have been poured to the desired height, the voids therein formed by

the tubes in the form are filled with coal, charcoal or coke which is ignited, the wall is draped with an asbestos tarpaulin, blowers are applied as previously described and the cooking continued. When the wall contains the correct amount of heat salt is applied to make the glaze and is cooled under the tarpaulin to minimize cracking.

As the clay is supplied to the form the heating units connected thereto will start to heat and cook the clay so that as the form rises the clay has started to harden and will be partially cooked when the desired height has been reached.

Forms can be made to cover openings under and about windows and doors, and the foundation is excavated and leveled before the forms are placed in position.

It is believed that the operation and construction of the form and the method for making the wall will be clearly understood by those skilled in the art and that modifications and changes in the arrangement and combination of the various parts used to carry out the invention may be resorted to without extending beyond the spirit and scope of the invention.

Having thus described the invention, what is claimed as new and desired to be secured by Letters Patent is:

1. A structure for constructing a wall comprising a form having outer side and end walls and a closed top, vertical tubes in said form, means for feeding material to said form, a frame for slidably mounting said form in said frame for vertical movement, and heating elements secured to said outer walls and the interior of said tubes.
2. The invention as in claim 1 wherein L-shaped beams are secured to the upper and lower edges of the form to function as a guide for said form, and upwardly inclined rods are secured to said lower L-shaped beams for supporting a tin liner and wire mesh.
3. The invention as in claim 1 wherein longitudinal slots are provided in the top of said form to permit a tin liner and wire mesh to be fed into said form.

DELMER WHITTENBERG.
